UNITED STATES PATENT OFFICE.

GEORGE PE COVER, OF COLORADO SPRINGS, COLORADO.

HOSE-NOZZLE.

No. 860,054.

Specification of Letters Patent.

Patented July 16, 1907.

Application filed January 10, 1906. Serial No. 295,374.

To all whom it may concern:

Be it known that I, GEORGE PE COVER, a citizen of the United States, residing at Colorado Springs, in the county of El Paso and State of Colorado, have invented 5 certain new and useful Improvements in Hose-Nozzles, of which the following is a specification.

My invention relates to improvements in hose nozzles, and refers to a nozzle particularly adapted for spraying purposes.

10 One object of the invention is the provision of a hose nozzle which may be applied to any ordinary hose coupling, and may be adjusted to throw a stream of water in the form of a spray, in any direction or at any angle desired.

15 Other objects of the invention are to provide a device for the purpose stated, provided with means for handling so that it may readily be carried from place to place, and which may quickly be secured in the desired location so as to project the stream of water in the 20 proper place.

With these and other objects in view, my invention consists of a nozzle, the bore of which is rectangular in cross section and tapering toward the small end of the nozzle, a paddle or deflecting plate pivotally secured 25 to the nozzle, an eccentric collar mounted on the nozzle and engaging the inner end of the plate, a handle secured to the nozzle, and a point or spike adapted for entering the ground.

My invention further consists in certain other novel 30 features of construction and combination of parts, substantially as disclosed herein.

Figure 1, is a side elevation of the nozzle with the spraying attachment and handle complete. Fig. 2, is a perspective view of the handle and driving point detached from the nozzle. Fig. 3, is an enlarged detail view of the eccentric collar for regulating the degree of pitch or angle of the deflector plate. Fig. 4, is a transverse sectional view of the nozzle, taken on line 4—4 of Fig. 1.

40 In the drawings: the numeral 1, designates the nozzle proper, the bore 2, of which, is rectangular in cross section and tapering toward the smaller end of the nozzle. The base of the nozzle is formed with the customary screw threads 3, adapting it to be applied 45 to an ordinary hose coupling of standard size.

On one side of the nozzle is formed a pair of ears 4, having an opening 5, therein. The paddle or deflector plate 6, is provided on one face with a lug 7, which is pivotally secured between the ears 4, by means of the 50 pin 8. The outer end of the plate extends beyond the end of the nozzle so as to be in the path of the stream issuing therefrom. Upon the nozzle about midway its length, are formed a pair of annular rings 9, between which is rotatably mounted, the eccentric ring or collar 55 10. A spring 11, on the deflector, presses against the

nozzle and causes the inner extended end of the deflector to engage the eccentric ring 10, and by turning this ring, the angle at which the stream is deflected, may be regulated with ease. The eccentric collar is formed in two parts which are pivotally connected together at 12, and at the opposite point, the members are secured by having a spring tongue 13, formed on one of the members, engage a complementary recess 14, formed in the other member. By means of this construction, the eccentric ring may be entirely removed from the nozzle if desired. 60

In order to readily handle the nozzle, I provide a bar or rod 15, having the handle or grasping portion 16, mounted thereon. At the front end, this bar is provided with a loop 17, adapted to fit over the end of the 70 nozzle. At the rear of the handle portion, the bar is bent downwardly and formed with a rounded portion 18, adapted to partially embrace the nozzle, and a semi-circular clasp 19, is pivoted to the bar at 20, and at the other end is secured to the bar, by the bolt fastening 75 21, thereby securely fastening the handle to the nozzle. The lower end of the bar is pointed as at 22, so that it may be driven into the ground, and an annular ring 23, is formed on the nozzle at the point where the bar encircles it, to further secure the bar against 80 displacement. A washer or gasket may be secured in the nozzle at the base of the threaded portion to prevent leakage.

The jet of water leaves the nozzle with great force 85 and being of rectangular form, it is readily deflected by the paddle and sprayed on the desired place without much waste in other directions.

By means of the handle, the nozzle may be readily transported about and anchored by inserting the spike in the ground, and by rotating the eccentric collar, the 90 desired amount of inclination or spray may be obtained.

From this description taken in connection with the drawings, it will be evident that I have accomplished all the objects herein set forth, and have provided a practical spraying device which is simple in construction and efficient in operation. 95

I claim:

1. In combination, a nozzle having a tapering rectangular bore, a pair of integral ears projecting from one side of the nozzle, a deflecting plate having a lug pivoted between said ears, the forward end of the deflector projecting in the path of the bore of the nozzle, a spring secured to the deflector engaging the nozzle forward of the pivotal point, a pair of rings encircling the nozzle, an eccentric annulus confined between said rings and engaging the 100 rear end of the deflector, said annulus consisting of two hinged members, a shoulder formed on the nozzle, a handle having loops engaging near the end of the nozzle and the shoulder thereon, and a spike formed integral with the handle. 105

2. A nozzle having a pair of ears on one side thereof, a deflecting plate provided with a lug pivoted between said ears, a spring carried by the deflecting plate en- 110

gaging the nozzle, a pair of rings encircling the nozzle, and an eccentric annulus confined between said rings and engaging the deflecting plate.

3. A nozzle having a rectangular tapering bore and provided with a pair of ears on one side thereof, a deflecting plate having a lug pivoted between said ears and extending beyond the mouth of the nozzle, a spring carried by the deflecting plate engaging the nozzle, a pair of rings encircling the nozzle, and an eccentric annulus confined

between said rings adapted to adjust the angle of deflection of the deflecting plate. 10

In testimony whereof I affix my signature in presence of two witnesses,

GEORGE PECOVER.
